G. H. HEMPHILL

COMBINATION HEADLIGHT DIMMING AND SPOTLIGHT CONTROLLING MEANS

Filed Oct. 6, 1925

INVENTOR,
Grover H. Hemphill,
BY Howard S. Smith
His ATTORNEY

UNITED STATES PATENT OFFICE.

GROVER H. HEMPHILL, OF CINCINNATI, OHIO.

COMBINATION HEADLIGHT-DIMMING AND SPOTLIGHT-CONTROLLING MEANS.

Application filed October 6, 1925. Serial No. 60,812.

This invention relates to a combination headlight dimmer and spot-light control, being an improvement upon my device for this purpose illustrated and described in my application Serial No. 663,010, filed September 15th, 1923.

It is the principal object of the present invention to provide an extremely simple, compact and economical device for closing a spot-light circuit in an automobile at a predetermined time during the operation of dimming the headlights, the means for effecting this result being wholly enclosed within the casing.

Other important and incidental objects will be brought out in the following specification and particularly set forth in the subjoined claims.

In the accompanying drawings illustrating my invention, Figure 1 is a side elevational view of my dimming device and spot-light control, with one side of the resistance-containing casing removed. Figure 2 is a cross sectional view taken through the casing on the line 2-2 of Figure 1. Figure 3 is a longitudinal, sectional view taken through the casing on the line 3-3 of Figure 1. Figure 4 is a sectional view taken through one end of the casing, showing how the dimmer may be locked in a predetermined position. And Figure 5 is a wiring diagram, showing the circuits in which my device is included.

Referring to the accompanying drawings for a detailed description of my invention, the numeral 1 designates a suitable metallic casing which is preferably rectangular in cross section and closed at one side by a removable plate 2. Secured to the rear wall of the casing 1 by screws 3, nuts 4 and washers 5 is an insulating block 6. Between the latter and one end of the case sufficient space is left for the vertical movement of a rod 7 which freely passes through a hole in the top wall and a hole in the bottom wall of the case 1. Secured to the top of the rod 7 is a mushroom-shaped head 8 adapted to be engaged by the foot of an automobile driver to depress the rod against the tension of a coil spring 9 surrounding the rod between its head 8 and a washer 10 on a member 11 such as an automobile floor board, to which the case 1 is attached. (See Figure 1).

The lower end of the rod 7 is threaded to receive two nuts 12 and 12^a respectively, the nut 12 being on the outside of the case to limit the upward movement of the rod 7, while the nut 12^a is on the inside of the case to limit the downward movement of said rod. These nuts may be adjusted on the rod to stop it at a desired point in its upward or downward travel. (See Figure 1).

Secured to one end of the insulating block 6 by screws 13 and 14 is a flat insulating piece 15 around which there is passed a wire 16 to form a flattened resistance helix, one of whose ends is connected to the screw 13 and the other to the screw 14. (See Figures 1 and 3).

Turned over one end of the insulating piece 15 for attachment thereto by the screw 13, so as to be in contact with the end of the wire 16 received by the latter, is a metal conducting strip 17. Over the other end of the insulating piece 15, for attachment thereto by the screw 14, there is turned a metal conducting strip 18 which contacts with the end of the wire 16 that is received by the screw 14. (See Figures 1, 2 and 3).

Secured to the insulating block 6 near the rod 7, is a pin 19 on which there is pivoted a contact arm 20, the rear end of which is bifurcated to freely fit a screw 21 secured to the rod 7. Between the head of this screw 21 and the bifurcated portion of the arm 20 is a washer 22. The free end of the arm 20 is turned inwardly for circular travel in contact with the flattened helix 6. This free end of the arm 20 is held in tensional engagement with the helix by a spring 23 coiled around the pin 19 between a washer 24 on its outer end and the arm. The outward movement of the washer 24 is limited by a cotter pin 25 passed through a hole in the pin 19. Between the contact arm 20 and the insulating block 6 is a collar 26 against which the contact arm is pressed by the spring 23, and between the collar 26 and the insulating block there is connected to the pin 19 one end of a metal conducting strip 27 which leads to, and is connected with, the screw 13. (See Figure 1).

Secured to the lower right hand corner of the insulating block 6 is an outwardly projecting screw 28 to which there is attached a spring contact arm 29. The inner end of

the latter is firmly pressed against the insulating block 6 by a washer 30 which is engaged by a nut 31 on the screw 28. The outer end of the contact arm 29 is curved upwardly into the path of horizontal movement of the contact arm 20 so that it may be engaged by the latter at a point approximately midway in the travel of the contact arm 20 over the helix 16, for a purpose to be hereinafter described. In order that the free

end of the arm 20 may be held stationary at this point, the rod 7 is notched to provide a shoulder 32 which, when the rod 7 is kicked outwardly, will engage the under part of the top of the wall of the case 1. The arm 20 will then be maintained with its free end at the middle of the helix 16 until said arm is released by kicking it in the opposite direction. (See Figure 4).

While my device may be employed for other purposes, its principal use is that of a headlight dimmer and spot light control for automobiles. If it is to be used on an automobile, there is secured to the contact screw 14 one end of a wire 33 which leads to a headlight 34 as shown by the wiring diagram in Figure 3, a companion headlight 35 being included in the same circuit by a wire 36 connected to the wire 33. From these headlights 34 and 35 lead connected ground wires 37 and 38 respectively.

Connected to the contact screw 13 is a wire 39 which leads to a dash switch 40 that is in turn connected by a wire 41 to one terminal of a storage battery 42, the opposite terminal of which is connected to ground by a wire 43. Connected to the contact screw 28 is a wire 44 that leads to a spot light 45 which is grounded by a wire 46. (See Figure 3).

When it is desired to dim the headlights 34 and 35, the pressure of the foot is exerted downwardly upon the rod 7 to move the free end of the arm 20 upwardly over the helix 16. The greater the distance the arm 20 is moved by the foot-depressed rod 7, the more resistance will be included by the helix 16 in the circuit defined by the ground, battery 42, wire 41, switch 40, wire 39, screw 13, conducting strip 27, pin 19, contact arm 20, wire 16, contact screw 14, wires 33 and 36, headlights 34 and 35 and wires 37 and 38 which lead to the ground. And in proportion as such resistance is included in the headlight circuit, the more the headlights 34 and 35 will be dimmed.

For the purpose of automatically illuminating the spot light 45 when the headlights 34 and 35 have been dimmed a desired amount, the free end of the arm 29 is positioned to be engaged by the contact arm 20 at the time the headlights 34 and 35 are well dimmed. (See the dotted arrow in Figure 3.) Immediately the arm 20 contacts with the upwardly projecting free end of the stationary arm 29, the spot light 45 will be in-

cluded in the headlight circuit by the connections previously described, to illuminate it.

The outer end of the contact arm 20 is free to be moved over the helix 16 to its dotted position in Figure 3, whereupon all of the resistance offered by the helix 16 will be thrown in the headlight circuit, while at the same time the spot light will be illuminated. 75

It will now be seen that I have provided a headlight dimmer and spot light control in which all of the resistance and contact elements are compactly mounted in the control casing. 80

Having described my invention, I claim:

1. A dimmer rheostat comprising a casing, an insulating member secured therein, a resistance winding on said member, a contact arm pivoted within said casing, for engagement with the resistance winding, means for shifting said contact arm to different positions on the resistance winding, and a second contact arm fixedly secured within the casing for automatic engagement by the first contact arm when the latter is at a desired point on the resistance winding. 85

2. A dimmer rheostat comprising a casing, an insulating member secured therein, a resistance winding on said member, a contact arm pivoted within said casing, for engagement with the resistance winding, means for shifting said contact arm to different positions on the resistance winding, and a second contact arm fixedly secured within the casing below the first contact arm, the free end of the second contact arm projecting upwardly for automatic engagement by the first contact arm when the latter is at a desired point on the resistance winding. 100

3. A dimmer rheostat comprising a casing, an insulating member secured therein, a resistance winding on said member, a contact arm pivoted within the casing for circular travel with its free end in engagement with said winding, longitudinally movable means to which said contact arm is pivotally secured, for turning the latter, and a second contact arm fixedly secured within the casing below the first contact arm, the free end of the second contact arm projecting upwardly for automatic engagement by the first contact arm when the latter is at a desired point on the resistance winding. 110

4. A dimmer rheostat comprising a casing, a flat insulating member secured therein, a helical resistance winding on said flat insulating member, a contact arm pivoted within the casing for circular travel with its free end in engagement with said winding, a longitudinally movable rod to which said contact arm is pivotally secured, for turning the latter, and a spring contact arm fixedly secured at one end within the casing, with its other end projecting upwardly for auto- 125

matic engagement by the first contact arm when the latter is at a desired point on the resistance winding.

5. A dimmer rheostat comprising a casing, a longitudinally movable operating member in said casing, a resistance in the latter parallel with the operating member, means connected to said operating member for sliding

contact with said resistance, and a contact member adapted to be engaged by said contact means on the operating member after said contact means has traveled a fixed distance in engagement with the resistance. 10

In testimony whereof I have hereunto set my hand this 30th day of September, 1925.

GROVER H. HEMPHILL.
